(57) **CLAIM**

The ornamental design for mounts for an LED bulb, as shown and described.

DESCRIPTION

FIG. 1 is a perspective view of a first embodiment of mounts for an LED bulb;

FIG. 2 is a side view of the first embodiment;

FIG. 3 is a top view of the first embodiment; and,

FIG. 4 is a bottom view of the first embodiment.

The broken line showing of the other portions of the bulb is included for the purpose of illustrating only and forms no part of the claimed design.
